APPARATUS FOR HANDLING CONCRETE

Filed Nov. 20, 1939

UNITED STATES PATENT OFFICE

2,274,225

APPARATUS FOR HANDLING CONCRETE

Cecil J. White, Minneapolis, Minn.

Application November 20, 1939, Serial No. 305,317

4 Claims. (Cl. 94—46)

My invention comprises a method and apparatus for preventing the segregation of the larger particles of the concrete mixture during the deposit of the mixture upon a supporting medium from a hopper or the like.

My invention also comprises a method and apparatus for preventing the larger particles of the aggregate of a paving mixture from lodging against the side forms or transverse joints in a slab or other structure. The lodgment of such large particles of the aggregate prevents the proper deposit and entrance of sufficient mortar at such locations to fill all the voids existing between the larger particles, and my invention guides the larger particles into the interior of the mass of material and permits the finer particles to lodge against the side forms or transverse joints.

My invention also comprises a method and apparatus for retaining a material, such as a sheet of joint material used in roadways and other structures, in proper desired position during the deposit of the concrete, and simultaneously preventing the larger particles of the concrete or other mixture from lodging against the form material, blocking off the deposit and entrance of sufficient mortar at such location to fill all voids between the large particles but guiding the large particles into the intermediate body of the mixture, permitting the finer particles of the mixture to lodge against the joint material.

My invention also comprises a construction of the holder for such joint material in a manner that will hold the joint material in proper position during the deposit of the concrete but also permitting the holding device to be easily removed after the concrete has been deposited. My apparatus may also be used against the side forms utilized in concrete roadway construction, for the practice of my method, in preventing the formation of voids and stony pockets at the sides and corners of the slabs or other structures.

The deposit of concrete upon a supporting medium such, for example, as the prepared subgrade of a highway, involves the problem of preventing the formation of segregated pockets consisting of volumes of the coarser aggregate of the mixture in which the voids between the large particles are not completely filled with mortar. Ordinarily when concrete is discharged from the lower restricted throat of a hopper or concrete mixer bucket, there is a tendency for some of the larger aggregate to become segregated from the mixture and to roll down and lodge at the toe of the deposited mixture. Especially when the

hopper is the bucket of a paving mixer, this hopper is propelled longitudinally over the subgrade and at a predetermined elevation above the subgrade. The hopper is so manipulated that it tends to distribute the batch of concrete rather uniformly over the subgrade in an elongated, flattened pile, thereby reducing the labor of distributing the mixture between the side forms. I have found that when concrete is so deposited, 5 the larger particles of the aggregate tend to separate from the mixture and to roll down the sides of the pile or mass and to accumulate at the toes or edges of the pile in rows or ribs of segregated masses. After the deposit of the first material is completed in this manner, it is supplemented by manual distribution of the material laterally, with the result that richer portions of the concrete are placed upon these segregated portions of the larger aggregate. The pavement 10 slab is then completed, leaving these rows or ribs of segregated material in the lower strata of the concrete slab, and the voids in this segregated material are then not completely filled with the mortar. This results in a pavement slab which has large void or honeycombed volumes of considerable length and width which weaken the slab structurally and likewise permit the ingress of water which may later freeze, disintegrating the slab.

20 I have found that by the use of my invention, the segregation of the larger aggregate from the mixture is prevented, since the larger aggregate is retained within the body of the mixture during the deposit thereof upon the subgrade so that upon completion, the slab is of a uniform 25 mixture throughout, free from voids and honeycombs and of uniform strength and density.

In the construction of concrete roadway slabs upon a prepared subgrade, the lateral edges of 30 the slab are shaped by what are commonly called longitudinal side forms anchored to the subgrade and defining the direction and height of the edges of the slab. At selected intervals in the length of the slab, there are placed contraction 35 and expansion joints, the latter in many cases consisting of a vertical sheet or strip of a compressible and expansible mastic material extending from the subgrade upward almost to the upper finished surface of the slab. These joints are 40 disposed transversely to the axis of the roadway and extend from one side form across the slab to the opposite side form. I have found that when concrete is deposited in the slab in the usual manner upon the subgrade between the 45 forms and against the transverse joints, the larger

particles of the aggregate tend to become segregated from the mixture and to become deposited against the side forms and against the transverse joints, especially in the corners and at the lower edges of the slab. Although the concrete is later brought to desired finished surface elevation against the side forms and against the transverse joint, the mortar does not flow readily into the voids of these segregated volumes, with the result that honeycombs and stony pockets, having a deficiency of mortar, exist at these critical locations when the slab has been completed.

The apparatus employing my invention is shown in the accompanying drawing, in which:

Figure 1 is a perspective view of a bar carrying downwardly inclined fingers, which bar is adapted to be mounted on the inside of the hopper in such a way that the fingers guide the larger pieces of aggregate toward the interior of the mixture being discharged from the hopper;

Figure 2 is a vertical sectional view illustrating the hopper equipped with the fingers shown in Figure 1 and held above a supporting medium upon which the concrete is deposited;

Figure 3 is a vertical sectional view taken on the line 3—3 of Figure 2;

Figure 4 is a vertical elevational view of another form of my apparatus;

Figure 5 is a top plan view of a portion of the apparatus of Figure 4;

Figure 6 is a vertical cross sectional view taken on the line 6—6 of Figure 4, and

Figure 7 is a perspective view of another form of my apparatus.

In the drawing, Figure 1 shows a bar indicated by the numeral 1 supporting a plurality of downwardly inclined fingers 2. In Figures 2 and 3 I have shown a bucket or hopper 3 such, for example, as the bucket of paving mixers. Bars 1 are bolted or otherwise secured to the inner faces of the walls 4 of the bucket 3 just above the lower edges of the walls surrounding the discharge orifice of the bucket. The fingers 2 extend inwardly and downwardly at the orifice. The fingers are so spaced that they permit the portion of the mixture consisting of the finer particles thereof to pass between them for discharge upon the subgrade 5. The original concrete mixture is indicated at 6 of Figure 2 and the larger particles at 7. The spacing of the fingers 2 is such as to prevent the larger particles 7 from passing between the fingers 2. Consequently, during the flow of the material 6 downwardly from the bucket 3, the larger particles 7 are guided toward the interior of the mass so that when the concrete 6 is deposited upon the subgrade 5 these larger particles 7 are retained within the body of the mass 6 and are not separated therefrom at the toe 8 of the deposited mixture. In Figure 3 I show the bucket 3 being propelled horizontally in the direction of the arrow 9.

In Figures 4, 5 and 6, I show the bar 10 having the downwardly inclined fingers 2, the bar 10 performing essentially the same function as bar 1 of Figure 1. In Figures 4, 5 and 6, the bar 10 is shown consisting of two parts 11 which together form an inverted U, having downwardly projecting legs to which are attached the fingers 2. At either end of the parts 11, I attach the sustaining members and handles 12. The parts 11 may be provided with the hinges 13 by means of which the downwardly extending legs of the parts 11 may be opened or closed. I also pro-

vide the clamp 14 operating to hold together the parts 11 and 12 and spacer sleeve 14a between the parts 12, the clamp 14 being arranged for removal from the members 12 so that the parts 11 may be opened or closed with respect to each other. I may elect to use only one-half of the bar 10, consisting of one part 11 with its attached fingers 2. The handles 12 are provided with the grooves or notches 15 to engage the side forms 16. I also provide the joint material 17 alongside of which, as a stiffener, I provide the vertical plate 18. I likewise provide the clamping channel 19 to hold the material 17 and the plate 18 in desired juxtaposition. It will be seen that the bar 10, consisting of the parts 11 (especially as shown in Figure 6), sustain and hold the clamping channel 19 and thereby sustain the joint material 17 in the desired position. The fingers 2 may extend downwardly to make contact with the subgrade 5 to assist in bracing the joint material 17 against lateral deflection and distortion.

In Figure 6, I show the concrete 6 containing the large particles 7 and the finer materials 20. I also indicate the space 21 between the fingers 2 and the joint material 17, into which spaces 21 the finer materials 20 have been permitted to pass while the larger particles 7 have been restrained by the fingers 2 to a position within the body of the materials 6. In the manipulation of the apparatus shown in Figures 4, 5 and 6, the joint material 17 with its plate 18 and clamping channel 19 is placed in position upon the subgrade 5 extending between the side forms 16 and the parts 17, 18 and 19 are held in rigid position by means of the downwardly extending parts 11 of bar 10, which is sustained and fixed upon the side forms 16 by means of the notch 15. Concrete 6 is then deposited upon the subgrade 5 in the manner hereinbefore described, and when the surface 22 of the concrete 6 has been properly obtained, the clamp 14 is removed and then by means of the handles 12 the bar 10 with its attached parts are extracted from the concrete 6, after which normal finishing and tooling operations are continued.

In Figure 7, I show a different form of my apparatus arranged to be used in conjunction with the side form 16. I provide the bar 23 having an inverted U-shaped cross section which is placed upon the upper rail 24 of the form 16, the bar 23 having the downwardly projecting legs 25 attached to which are the downwardly inclined fingers 2. This bar 23 with its fingers 2 would serve the same function with respect to the side forms 16 that bar 10 with its fingers 2 performs with respect to the joint material 17 of Figures 4, 5 and 6.

While I have used a paving mixer bucket for the purpose of illustrating the manner in which my invention may be used, as shown in Figures 1, 2 and 3, it will be understood that the invention may be employed in a great variety of other commercial equipment. Likewise, while in Figures 4, 5, 6 and 7 I have utilized the forms and joints normally utilized in the construction of concrete roadway slabs, it will be understood that my invention may be used in a great variety of other forms of construction. My invention may also be employed in conjunction with spouts, chutes or elephant trunks, for the deposit of concrete or other mixtures into forms or other positions where the concrete is to be utilized.

Having thus described my invention, I now

claim and desire to secure by Letters Patent of the United States:

1. In apparatus for treating material, such, for instance, as concrete which contains particles of varying sizes, for the purpose of preventing movement of the larger particles to the outside of the mass and segregation of such larger particles from the mass during deposit of the material, a container for holding the material and for dropping it upon a lower place of deposit, a series of suitably supported members projected from the outside into the outer part of the downwardly moving mass, said members being inclined downwardly from the outer limits of the container toward the inner part thereof and being spaced apart to guide the larger particles downwardly and inwardly and to permit passage between them of the remainder of the moving mass and being of such length as to permit the free passage of the larger particles over their inner ends.

2. In apparatus for treating material such, for instance, as concrete which contains particles of varying sizes, for the purpose of preventing movement of the larger particles to the outside of the mass and segregation thereof from the mass during deposit of the material, a container having walls and having a discharge orifice at its lower part and a series of guide members suitably mounted and projecting into the path of the material discharged from the orifice, said members being inclined downwardly from the outer part of said orifices toward the inner part thereof and being successively spaced apart to guide the larger particles downwardly and inwardly in said path and to permit passage be-

35 tween them of the remainder of the moving mass, and being of such length as to permit the free passage of the larger particles over their inner ends.

3. In a device of the class described, a supporting means designed to be placed adjacent the path of a mass of material containing particles of various sizes and moving by gravity from one place to another, a series of opposed fingers suitably mounted on a support and inclined inwardly and downwardly, a hopper having a low orifice and supported above said fingers, whereby materials deposited from said orifice pass said fingers, said fingers spaced apart to prevent passage of the larger particles between the successive fingers and to guide such particles toward and over the lower ends of said fingers, and to permit the passage of smaller particles between the successive fingers.

20 4. In a device of the class described, a supporting means designed to be placed adjacent the path of a mass of material containing particles of various sizes and moving by gravity from one place to another, a frame having opposed sides, a series of fingers mounted on said sides and inclined inwardly and downwardly, a hopper having a low orifice supported above said frame, whereby materials deposited from said orifice pass said fingers, said fingers spaced apart to prevent passage of the larger particles between 25 the successive fingers and to guide such particles toward and over the lower ends of said fingers, and to permit the passage of smaller particles between the successive fingers.

CECIL J. WHITE.
